UNITED STATES PATENT OFFICE

SIDNEY J. FINN, OF BEVERLY, MASSACHUSETTS, ASSIGNOR TO UNITED SHOE MACHINERY CORPORATION, OF PATERSON, NEW JERSEY, A CORPORATION OF NEW JERSEY

SHEET-SEPARATING APPARATUS

Application filed December 5, 1928. Serial No. 323,909.

This invention relates to apparatus for separating adhering sheets of material, a particularly useful application being found in connection with rubberized insoles for shoes, 5 to which insoles are attached protective sheets of paper. In producing such work-pieces, a stack of sheets of insole-material, separated from one another by sheets of paper to prevent them from sticking together, are subjected to the action of a dieing-out apparatus, each die cutting simultaneously a plurality of insoles. Each of the cut insoles ordinarily bears upon its coated face a cut paper piece, and this must be removed before 10 the insole is utilized. This separating operation, as it has been performed manually, consumes considerable time, since the adhesion is strong, especially at the edges, where the die forced the sheets together in making the cut. An object of my invention is to provide improved mechanism by which the effective separation of adhering sheets may be performed much more speedily than when done by hand.

25 For the attainment of the above object, my improved separating apparatus has a novel organization of opposite movable members, these preferably rotating, each provided with a portion arranged to enter and separate adjacent sheets, as the insole and the attached paper. As herein illustrated, each member is in the form of a roll, while sheet-engaging projections are furnished by fingers which are hooked and are movable in the roll. An 30 abutment against which each roll operates is, in the present embodiment of the invention, furnished by the companion roll. The fingers are projected through openings in the rolls, as they approach the bite of said rolls, or the opposite abutment member, this being to engage and separate the material from the associated layer, and are withdrawn as they travel from this roll or abutment member to release the separated layer. This movement of the fingers may be effected by eccentric means. Preferably, the fingers act against yieldable material, this being shown as provided by belts extending about and to one side of the opposite roll. These belts not 35 only facilitate the entrance of the fingers into the sheets by virtue of the yield, but also, by their relation to the roll, strip or deflect the sheets therefrom. I have found that the action of the fingers is most certain when their hooked ends are turned rearwardly, or 40 in a direction opposite to that in which they revolve. To facilitate penetration of the sheet-material by the fingers, it is thrust toward them, as by advancing it at a rate greater than that at which the entering ends travel. The advancing means may also act to loosen the material in preparation for its separation. For this purpose, I have illustrated corrugated rolls, which bend the 45 sheets. This loosening is most complete when the sheets are bent in directions substantially at right angles to each other, as by rolls longitudinally and circumferentially corrugated. Since the protective sheets are commonly coated with paraffin or some 50 other wax, the loosening of these from the sheets of stock is further facilitated, or may be wholly effected, by heating means which cooperates with the separating means. I have shown members associated with one of 55 the separating rolls and situated at different horizontal levels, to receive separated sheets, while between the receiving members, and cooperating with the roll, is a guide member, which assists in directing the sheets in their 60 delivery.

65 One of the many forms which my invention may assume is illustrated in the accompanying drawings,

70 Fig. 1 showing the apparatus in side elevation;

75 Fig. 2 being a longitudinal vertical section;

80 Fig. 3 illustrating the separating rolls in side elevation, with parts broken away;

85 Fig. 4 being a partial transverse section through one of the rolls; and

90 Fig. 5, a perspective view of the work to be operated upon.

95 Upon the opposite sides of a frame 10 are rotatably mounted the more essential elements of the apparatus. First, there is a horizontal feed-table 12 projecting from one extremity of the frame, this being followed by a pair of feed-rolls 14, 14 turning about 100

horizontal axes. The journals 15 of the lower roll rotate in fixed bearings, while the bearings of the upper roll are yieldable, there being springs 16 surrounding rods 18 rising 5 from the bearing-blocks and being interposed between said blocks and a cross-bar of the frame. The rods move vertically through openings in these bars. Both rolls 14 are shown as having hollow shafts 15 within 10 which are heating units 17, preferably electrical and supplied with current through conductors 19. The effect of the heat upon the work passing between the rolls will herein-after be explained. Following the rolls 14 15 is a pair of rolls 20, 20, which are longitudinally corrugated, having intermeshing projections 22. These rolls, by alternately bending the sheets in opposite directions, having the effect of slipping the layers over each 20 other, so they become loosened. These loosening rolls are journaled similarly to the feed-rolls, except that their bearing rods carry nuts 24 upon their threaded ends. This arrangement permits the spacing between the 25 rolls of the pair to be varied, thus producing depressions of different depths in the material, and consequently different loosening effects. From the rolls 20, the advancing sheet-material enters between rolls 26, 26 pro- 30 vided with circumferential corrugations 28. These bend the sheets in a direction at right angles to the depressions made by the rolls 22, very effectively completing their preliminary separation. The mounting of the rolls 35 26 may be identical with that of the rolls 20. Power may be applied to the shaft of the lower roll 26 through a pulley 30. A train of gearing 32, including intermediate idlers, communicates rotation to the lower rolls 20 40 and 14, and pairs of gears 34 turn the upper rolls of all pairs oppositely to the lower rolls. The effect throughout is to advance the work from the table 12. The teeth of the gears 34 are of such length as to permit the adjustment 45 of the upper rolls without destroying the proper working engagement.

From the feeding and loosening section of the apparatus, the material is delivered to means for fully separating the adjacent 50 layers from each other. Here, an apron 36 guides the work to a pair of horizontally journaled upper and lower rolls 38 and 40. Structurally, these may be the same, consisting of heads 42 joined by peripheral bars 44 55 spaced from one another to leave longitudinal openings 46. The rolls are rotatable in opposite directions about stub-shafts 48, those for the lower roll being fixed in the frame, while those for the upper are ar- 60 ranged to yield vertically, as in the preceding roll-pairs. Gearing 50 connects the roll 40 to the gear-train 32, this roll 40 being geared to its companion roll at 52. The outer di- 65 ameters of the rolls 26 and of the rolls 38, 40 are such that the former turn at a greater

peripheral speed. The reason for this will be developed later. Journaled in the inner ends of each pair of shafts 48, eccentrically with respect to the heads 42, is a shaft 54 toothed at 56 over the periphery of the portion between its reduced ends. Supported by and compelled to turn with the shaft are separating fingers 58 with enlargements 60 complementally toothed to engage the shaft 54. Their outer extremities extend into the 70 openings 46 and are hooked at 62, being turned in a direction opposite to the rotation of the roll. The rolls 38 and 40 and the shafts 54 are compelled to turn together by plates 63 keyed to the shafts near one of the heads of each roll and having peripheral projections entering the corresponding spaces 46. The projections so fit within the spaces that the fingers 58 are relieved of any substantial pressure against the walls of the openings. The eccentricity between the rolls and the shafts 54 is such as to cause the periphery of each roll and its associated fingers simultaneously to follow, respectively, the paths indicated at *a* and *b* in Fig. 4 of the drawings. This leads to the alternate projection of the hooked ends of the fingers through the openings and their withdrawal to points between the bars. The first movement occurs as the fingers approach the bite of the rolls, continuing during the separating action and being at a maximum when the fingers occupy substantially vertical positions, this being followed by their retraction as they separate from the horizontal line of feed. The fingers are arranged in helical series about the entire peripheries of the rolls, those which succeed one another along the shafts operating in successive spaces circumferentially of the rolls. The series of 90 fingers is interrupted longitudinally of each roll by circumferential depressions 64 in the bars 44, in which depressions run endless belts 66 of some such yieldable material as rubber. These depressions and belts are staggered upon each roll with respect to those of the opposite roll, thus causing the hooked ends of each of the divided or secondary series of fingers to register with and operate against a yieldable surface. The belts upon the roll 38 pass over alined grooves in a roll 68 journaled upon arms 70 projecting forwardly and upwardly from the frame 10. I prefer to construct the arms in sections 100 connected by screws 72 passing through slots, this allowing the roll 68 to be separated from the roll 38 and the belts 66 correspondingly tightened. Journaled in the arms 70, or in brackets secured thereto, is a roll 74, which 110 may be of rubber. This roll forms, with the adjacent surfaces of the belts, a throat in which may be received sheets of paper sometimes found sticking to the uncoated sides of the work, while the insole-pieces themselves are deflected below the roll. Rotation of the 120

130

roll is produced by its yielding contact with the belts. From the lower side of the frame depend brackets 76 held in place by slot-and-screw connections 78. A grooved roll 5 80 is journaled in the brackets and guides the belts 66 of the roll 40. Here, the tension of the belts is controlled by adjustment of the brackets 78 along the frame. Adjacent to the lower forward side of the roll 40 is shown 10 a small roll 82 similar to the upper roll 74 and rotated in the same manner. By this roll 82, the paper separated from the under side of the work is maintained for a time in contact with the roll 40 and directed in the 15 desired path. Preferably somewhat above the bite of the rolls 38, 40 is a horizontal receiving member, as a conveyor 84, for the work-pieces operated upon. Beneath the frame, a container 86 may be placed to receive 20 the protective layers carried by the coated sides of these pieces. At 88, just above the roll 74, appears a table, upon which may be deposited protective pieces adhering to the opposite sides of the work-pieces.

25 In Fig. 5 is illustrated an example of the adhering sheets of material which my apparatus is adapted to separate. These consist of a work-piece S, in the form of an insole, while a protective piece s of paraffin- 30 paper adheres to its under, coated side. In subjecting this assembly to the action of the hereinbefore described apparatus, the insole is laid upon the table 12 with the paper piece downward, and is forced forward, end first, 35 between the rolls 14, 14, which with the succeeding rotatable members turn in the direction of the arrows in Fig. 2. The heat to which the work is subjected by the units 17 in the rolls 14 renders the coating of the 40 paper s more or less fluid, greatly decreasing its adhesion to the insoles S. The work is then advanced to the longitudinally corrugated rolls 20, which apply to it a succession of transverse bending actions, this having 45 a tendency to further reduce the adhesion and displace the pieces relatively to each other. From the rolls 20, the now partially separated sheets enter the circumferentially corrugated rolls 26. Here, an action similar 50 to that just described takes place, except at right angles thereto. The insole, with the paper now thoroughly loosened, travels, under the influence of the rolls 26, across the apron 36 and between the rolls 38 and 40. 55 At this point, the hooked portions 62 of the fingers 58 are projecting beyond the peripheries of the rolls and are revolving more slowly than the advancing material travels. This is consequently buckled transversely and 60 forced against the hooks, those of the roll 38 entering the insole, while those of the roll 40 penetrate the paper. Because of the helical arrangement of the series of fingers, the sheets always find a plurality of the hooks at the 65 bite ready to penetrate them. The engage-

ment of these hooks with the layers is perfected by the pressure of the finger-ends against the yieldable material of the belts 66. As the pieces pass beyond the rolls 38, 40, the hooks raise the insole S and draw 70 down the paper s, retaining and thus separating them completely. As rotation continues, the fingers are withdrawn through their openings 46 by the action of the eccentric-mounting, and the weight of the sole 75 causes its end to descend, being, if necessary, deflected downwardly by the roll 74. This roll acts upon the partly separated soles as would a fixed member, contact with its under side preventing said sole from being carried up by the paper from which it hangs. The sole then falls upon the conveyor 84, which may deliver it directly for an operation upon it, as to a cementing machine. The 80 paper is carried down not only by the hooks, but by the attractive force generated by static electricity in the belts, and enters between the rolls 40 and 82, being directed by the latter toward the container 86. The 85 weight of the paper may break the adhesion to the belt 66 before the roll 80 is reached. If not, the change of direction at said roll permits its weight to exert a sufficient separating action, whereupon it falls and is received by the container. Sometimes insoles 90 come to the apparatus with paper upon the uncoated as well as upon the coated side. In this case, the hooks of the roll 38 leave the insole before they do this upper layer 95 of paper, so that the latter is retained longer 100 in contact with the roll and is also held, as already pointed out in connection with the roll 40, by the static charge upon the associated belts. This keeps the paper in contact with the belts sufficiently to bring 105 its upper end above the roll 74, which guide it above the table 88, upon which it falls, because of its weight, before it passes over the roll 68.

Having described my invention, what I 110 claim as new and desire to secure by Letters Patent of the United States is:

1. In a sheet-separating apparatus, cooperating rolls arranged to receive between them adhering sheets, and sheet-separating 115 projections carried by each roll and extending in a series about the entire periphery.
2. In a sheet-separating apparatus, cooperating rolls arranged to receive between them adhering sheets, and sheet-engaging 120 hooks carried by each roll.
3. In a sheet-separating apparatus, a rotatable member provided with a portion arranged to engage and separate a sheet of material from an adjacent sheet, means for moving the engaging portion upon the member during the separating action, and means for retaining the adjacent sheet against movement with the engaged sheet.
4. In a sheet-separating apparatus, opposite 130

rotatable members each provided with a portion arranged to enter and separate adjacent sheets, and means made effective during the separating action for moving the portion 5 upon the member by which it is carried.

5. In a sheet-separating apparatus, a rotatable roll, sheet-engaging projections movable upon the roll, means operable under the power of the apparatus for moving the projections and an abutment member cooperating 10 with the roll.

6. In a sheet-separating apparatus, opposite rotatable rolls, sheet-engaging projections mounted upon the rolls, and means acting 15 simultaneously upon the projections of the rolls for moving the projections of each of said rolls toward and from the opposite roll.

7. In a sheet-separating apparatus, an 20 abutment member, a movable roll cooperating with the abutment member and having openings, sheet-engaging fingers operating in the openings, and means made effective during the movement of the roll for causing the projection and withdrawal of the fingers through 25 the openings.

8. In a sheet-separating apparatus, an abutment member, a movable roll cooperating with the abutment member and having openings, sheet engaging fingers having hooked 30 ends operating in the openings, and means for projecting and withdrawing the hooked ends through the openings.

9. In a sheet-separating apparatus, an 35 abutment member, a movable roll cooperating with the abutment member and having openings, sheet-engaging fingers operating in the openings, and means for projecting the fingers through the openings as they approach 40 the abutment member and for withdrawing said fingers as they retreat from the abutment member.

10. In a sheet-separating apparatus, opposite rotatable rolls each having openings, 45 sheet-engaging fingers operating in the openings, and means for projecting and withdrawing the fingers simultaneously through openings in both rolls.

11. In a sheet-separating apparatus, a rotatable roll having openings, sheet-engaging 50 fingers operating in the openings, and eccentric means for moving the fingers through the openings.

12. In a sheet-separating apparatus, a rotatable roll having openings, sheet-engaging 55 fingers operating in the openings, a support for the fingers rotatable within the roll, and bearings for the roll and support eccentric with respect to each other.

60 13. In a sheet-separating apparatus, a rotatable roll having openings, a sheet-engaging finger operating in the openings, a support for the fingers rotatable within the roll, and a bearing member provided with an exterior surface upon which the roll turns and 65

with an opening to receive the finger-support, said opening being eccentric to the exterior bearing-surface.

14. In a sheet-separating apparatus, an abutment member, and a rotatable roll cooperating 70 with the abutment member and having sheet-engaging projections arranged in a helix at its periphery.

15. In a sheet-separating apparatus, an abutment member, a rotatable roll cooperating 75 with the abutment member and having fingers arranged in a helix at its periphery, and means for rendering said fingers successively effective along the roll for engagement with the sheets.

16. In a sheet-separating apparatus, an abutment member, a rotatable roll cooperating 80 with the abutment member and having openings in its periphery, sheet-engaging hooks arranged helically about the axis of the roll and operating in the openings, and means for moving the hooks through the openings successively along the helix.

17. In a sheet-separating apparatus, opposite rotatable rolls, and sheet-engaging 85 fingers arranged in a helix about each roll.

18. In a sheet-separating apparatus, opposite rotatable rolls, each having openings in 90 its periphery, sheet-engaging fingers arranged helically about the axis of each roll and operating in the openings, and means for projecting the fingers through the openings successively along the helix at the bite 95 of the rolls and for withdrawing the fingers as they leave the bite.

19. In a sheet-separating apparatus, an abutment member, a rotatable roll cooperating 100 with the abutment member, a shaft extending through the roll and provided with teeth, and sheet-engaging fingers with portions surrounding the shaft and having teeth for engagement therewith.

20. In a sheet-separating apparatus, a revolvable sheet-separating finger, and a yieldable member against which the finger operates in separating the sheets.

21. In a sheet-separating apparatus, a rotatable roll, sheet-engaging projections carried by the roll, an opposite rotatable roll, and a yieldable member extending about the roll and cooperating with the projections.

22. In a sheet-separating apparatus, opposite rotatable rolls, series of sheet-engaging fingers carried by the rolls, and yieldable material carried by the opposite roll in engagement with each series of fingers.

23. In a sheet-separating apparatus, opposite rotatable rolls, series of sheet-engaging fingers carried by the rolls, each series being arranged in a helix, and yieldable material carried by the opposite roll in engagement with each helical series.

24. In a sheet-separating apparatus, opposite rotatable rolls, series of sheet-engaging fingers carried by each of the rolls, and yield- 130

- able material carried by the rolls between the series of fingers thereon and in registration with the series of fingers upon the opposite roll.
- 5 25. In a sheet-separating apparatus, a rotatable roll, sheet-engaging fingers spaced from one another along the roll, and an endless member passing about the roll between the fingers and extending to one side of said roll. 70
26. In a sheet-separating apparatus, a rotatable roll, series of sheet-engaging fingers spaced from one another along the roll, and a belt of yieldable material passing about the roll between the series of fingers and extending to one side of said roll. 75
- 15 27. In a sheet-separating apparatus, opposite rotatable rolls, series of sheet-engaging fingers spaced from one another along each roll, the fingers of one roll registering with the spaces of the other, and belts operating in the spaces and extending to one side of each roll. 80
- 20 28. In a sheet-separating apparatus, opposite rotatable rolls, series of sheet-engaging fingers spaced from one another along each roll, the fingers of one roll registering with the spaces of the other, and belts operating in the spaces and extending to one side of each roll, said belts being of yieldable material and furnishing abutment-surfaces against which the fingers act. 85
- 30 29. In a sheet-separating apparatus, revolute fingers constructed and arranged to penetrate the sheets, movable means for thrusting the sheets upon the fingers, and means for producing the thrusting movement of said means. 90
- 35 30. In a sheet-separating apparatus, a rotatable support, fingers movable upon the support and constructed and arranged to penetrate the sheets, means for thrusting the sheets upon the fingers, and means for moving the fingers upon the support to withdraw them from the sheets. 95
- 40 31. In a sheet-separating apparatus, revolute fingers constructed and arranged to penetrate the sheets, movable means for thrusting the sheets upon the fingers during their revolution, and means for operating said thrusting means. 100
- 45 32. In a sheet-separating apparatus, continuously revolute fingers constructed and arranged to penetrate the sheets, and means for advancing the sheets into engagement with the entering ends of the fingers at a rate greater than that at which said ends travel. 105
- 50 33. In a sheet-separating apparatus, revolute sheet-engaging hooks arranged to travel with the entering ends turned rearwardly, and a pair of rolls arranged to advance the sheets against the entering ends of the hooks. 110
- 55 34. In a sheet-separating apparatus, revolute sheet-engaging hooks arranged to travel with the entering ends turned rearwardly, a pair of rolls arranged to advance the sheets against the entering ends of the hooks, and means for moving the hooks away from the sheets. 115
- 60 35. In a sheet-separating apparatus, sheet-corrugating means for loosening adhering sheets from each other, sheet-penetrating means for engaging both loosened sheets, and means for moving the engaging means to separate the sheets. 120
- 65 36. In a sheet-separating apparatus, means for successively bending adjacent sheets, penetrating means arranged to enter opposite sides of adjacent sheets loosened by the bending, and means for moving the penetrating means to separate the sheets. 125
- 70 37. In a sheet-separating apparatus, means for bending adhering sheets in directions at right angles to each other, and sheet-separating means to which the bending means delivers. 130
- 75 38. In a sheet-separating apparatus, means for bending adhering sheets in directions at right angles to each other, and sheet-penetrating means to which the bending means delivers, the rate of movement of the delivering means being greater than that of the penetrating means. 135
- 80 39. In a sheet-separating apparatus, corrugated rolls between which the sheets are passed, and movable sheet-engaging fingers to which the rolls deliver. 140
- 85 40. In a sheet-separating apparatus, succeeding pairs of longitudinally corrugated and circumferentially corrugated rotatable sheet-loosening rolls, and movable sheet-separating fingers to which the rolls deliver. 145
- 90 41. In a sheet-separating apparatus, succeeding pairs of longitudinally corrugated and circumferentially corrugated rotatable sheet-loosening rolls, and opposite series of revolute sheet-separating fingers to which the rolls deliver. 150
- 95 42. In a sheet-separating apparatus, succeeding pairs of longitudinally corrugated and circumferentially corrugated rotatable sheet-loosening rolls, opposite rotatable separating rolls to which the loosening rolls deliver and hooks carried by the separating rolls and arranged to penetrate the sheets. 155
- 100 43. In a sheet-separating apparatus, succeeding pairs of longitudinally corrugated and circumferentially corrugated rotatable sheet-loosening rolls, opposite rotatable separating rolls to which the loosening rolls deliver, hooks carried by the separating rolls and arranged to penetrate the sheets, and means for rotating the loosening rolls to advance the sheets at a greater rate than that at which the hooks travel. 160
- 105 44. In a sheet-separating apparatus, a separating roll rotatable about a substantially horizontal axis, and members situated at different levels to receive separated sheets. 165
- 110 45. In a sheet-separating apparatus, a

separating roll rotatable about a substantially horizontal axis, members situated at different levels to receive separated sheets, and a guide member for the sheets cooperating with the roll between the receiving members.

46. In a sheet-separating apparatus, means for applying heat to the sheets, means for engaging opposite sides of the heated sheets, and means for moving the engaging means 10 in different directions to separate the sheets and simultaneously advance the separated sheets.

47. In a sheet-separating apparatus, unitary means for both advancing and applying heat to the sheets, and separating means 15 to which the heating means advances the sheets and which continues such advance.

48. In a sheet separating apparatus, means for applying heat to the sheets, means for 20 bending the heated sheets, means for engaging the bent sheets, and means for moving the engaging means to separate said sheets.

49. In a sheet-separating apparatus, means for applying heat to the sheets, movable 25 members penetrating the heated sheets, and means for moving the members to separate the sheets.

50. In a sheet-separating apparatus, a pair of rotatable rolls, heating units situated 30 within the rolls, and sheet-separating means receiving the heated sheets directly from the rolls.

In testimony whereof I have signed my name to this specification.
